US0D1099947S

(12) **United States Design Patent** (10) Patent No.: **US D1,099,947 S**
(45) Date of Patent: ** Oct. 28, 2025

(54) **DISPLAY SCREEN OR PORTION THEREOF WITH GRAPHICAL USER INTERFACE**

(71) Applicant: **10x Genomics, Inc.**, Pleasanton, CA (US)

(72) Inventors: **Ashkan Beyranvand Nejad**, San Jose, CA (US); **Caio Christovao Da Silva Porto**, San Jose, CA (US); **Katherine Habeck**, Belmont, CA (US); **Rushi Panchal**, Dublin, CA (US)

(73) Assignee: **10X GENOMICS, INC.**, Pleasanton, CA (US)

(**) Term: **15 Years**

(21) Appl. No.: **29/964,929**

(22) Filed: **Sep. 25, 2024**

CLAIM

The ornamental design for a display screen or portion thereof with graphical user interface as shown and described.

DESCRIPTION

The sole FIGURE is a front view of a display screen or portion thereof with graphical user interface showing our new design.

The outermost broken lines showing a display screen or portion thereof form no part of the claimed design.

1 Claim, 1 Drawing Sheet
